UNITED STATES PATENT OFFICE

2,513,509

SCREW DRIVER

Charles N. Morts, Fulton, Mo.

Application August 22, 1945, Serial No. 611,944

1 Claim. (Cl. 145—50)

1

The invention relates to a hand tool, and more especially to a screw driver.

The primary object of the invention is the provision of a tool of this character, wherein the handle is swiveled to the bit shank, and can be locked thereto, so that the tool can be turned for screw driver action or the handle can be freed and such tool operated under ratchet action imparted to the bit shank, either clockwise or counter-clockwise, for the driving of a screw into the work or removing therefrom.

Another object of the invention is the provision of a tool of this character, wherein it can be operated in congested places with ease and dispatch, the tool being of novel construction and unique in the assembly of its parts, these few in number, thus economical for repairs or replacements.

A further object of the invention is the provision of a tool of this character, which is simple in construction, combination and arrangement of parts, as will be hereinafter more fully described, illustrated in the accompanying drawings, which show the preferred embodiment of the invention and pointed out in the claims hereunto appended.

In the accompanying drawings:

Figure 1 is an elevation of the tool constructed in accordance with the invention.

Figure 2 is a vertical longitudinal sectional view through the same.

Figure 3 is a view similar to Figure 2 showing the tool in a different adjusted position.

Figure 4 is a sectional view taken on the line 4—4 of Figure 3 looking in the direction of the arrows.

Figure 5 is a sectional view taken on the line 5—5 of Figure 2 looking in the direction of the arrows.

Figure 6 is a sectional view taken on the line 6—6 of Figure 2 looking in the direction of the arrows.

Figure 7 is a sectional view taken on the line 7—7 of Figure 2 looking in the direction of the arrows.

Similar reference characters indicate corresponding parts throughout the several views in the drawings.

Referring to the drawings in detail, the tool constituting the present invention, comprises a straight shank 10, terminating at its outermost end in a screw driver bit or tip 11, of the usual construction, while the inner end portion of this shank 10 is centrally socketed within the innermost end of a handle stock 12, the socket 13 being of a reduced diameter with respect to a shank 15 being of a reduced diameter with respect to a shank 10.

chamber or cell 14 provided in the outer end portion of such stock. This chamber or cell 14 opens through the outer end of the stock 12 and is closed by a plug cap 15, which is detachably fitted to the latter. The cell or chamber 14 and the socket 13 are divided by an annular flange 16 internally of the stock 12, and this flange forms a bearing for a swivel head 17 on the inner end of the shank 10, so that the latter is swiveled to the said handle stock, as best seen in Figures 2 and 3 of the drawings.

Carried at the inner end of the stock 12 is a ring like track 18, which is secured in place by the countersunk fasteners 19 to such stock, while next to this track 18 is a flat faced wrench engaging nut 20, which encircles the said shank 10 and is made fast to the latter by a cross-pin 21. The nut 20 is adapted to be detachably engaged by a ratchet-acting wrench, only a portion 22 being shown thereof, so that the shank can be turned when the handle stock is free thereon, and this turning can be had in opposite directions through ratchet-action of the wrench under adjustment thereof, as is common thereto.

Provided in the socket 13 and in the shank 10, as well as the nut 20, at diametrically opposite points thereof are registering longitudinally disposed grooves or channels 23 having slidably fitted therein runners forming locking keys 24, which when manually shifted free of the grooves or channels 23 in the stock 12 permit the shank 10 to be turned independently of such stock, and this turning operation can be had through the use of the wrench when engaging the nut 20, as before described. Now, when the keys 24 are engaged with the grooves or channels 23 in the handle stock 12, the latter is locked fixed to the shank 10, and the latter can be turned by such stock.

The keys 24 are confined within the channels or grooves 23 by a coupling collar 25 interfitting therewith at the outer ends of the said keys.

The chamber or cell 14 can be used for holding accessories, if desired.

The tool is susceptible of service as a screw driver and is operable either with or without the wrench, as should be obvious.

What is claimed is:

A screwdriver comprising a handle portion having a shank socket and an enlarged bore, a shoulder formed at the junction of said socket and said bore, a screwdriver shank revolvably mounted in said shank socket, a member of polygonal cross section rigidly secured to said shank and slidably abutting an end of said

handle portion, head means on the end of said shank and rotatably mounted in the bore in said handle portion, said head means abutting said shoulder and said member abutting the end of the handle for rotatably retaining said shank on said handle portion, diametrically opposed grooves in said shank socket and extending lengthwise of the same, diametrically-opposite grooves in said shank and extending longitudinally thereof, said shank grooves adapted to be rotated into register with said shank socket grooves, elongated latching bars reciprocably mounted in said shank grooves and through said member, and an actuating ring about the latching bars retaining the same in said shank grooves and adapted to shift said bars in said grooves, whereby said elongated latching bars may be shifted along said shank grooves into or out of said shank socket for engaging or disengaging,

respectively, the grooves thereof whereby said shank will turn with said handle portion or rotate freely relative to the same.

CHARLES N. MORTS.
